TORQUE BALANCING OF JET PROPULSION TURBINE PLANT

Fritz Albert Max Heppner, Leamington Spa, and John Denis Voce and David Rhys Evans, Coventry, England, assignors to Armstrong Siddeley Motors Limited, Coventry, England

Application July 20, 1943, Serial No. 495,525
In Great Britain June 17, 1942

5 Claims. (Cl. 60—35.6)

1

This invention relates to an internal-combustion turbine plant for jet-propulsion purposes. As is well understood, such plant includes a compressor, a combustion chamber in which the compressed air is mixed with fuel and ignited, and a turbine driven by the burning gases and driving the compressor, the turbine exhaust forming the propulsion jet.

It is our main object to arrange for the more efficient operation of such a plant.

For a full understanding of this and other objects and advantages attention should be directed to the following description in which reference is made to the accompanying diagrammatic drawings, wherein:

Figure 1 is a fragmentary sectional elevation through an internal-combustion turbine jet-propulsion unit adapted according to the invention, the compressor being a three-stage axial-flow one;

Figure 2 is a fragmentary elevation of the diffuser blades of Figure 1 to which reference is made hereinafter;

Figure 3 is a fragmentary section taken mainly on the line III—III of Figure 1;

Figure 4 is a part-sectional elevation of another form of unit adapted according to the invention, in which the compressor is a simple axial-flow one.

Fig. 5 is a section on line 5—5 of Fig. 1;

Fig. 6 is a section on line 6—6 of Fig. 1;

Fig. 7 is a section on line 7—7 of Fig. 1;

Fig. 8 is a section on line 8—8 of Fig. 1; and

Fig. 9 is a section on line 9—9 of Fig. 4.

According to the invention, the unit has a shell carrying internally some of the turbine blades and rotating in the opposite direction to that of a rotor which carries some of the compressor blades (within the shell) or other of the turbine blades (within the shell), and the shell drives external blades coacting with stationary blades by reaction from stationary blades coacting directly or indirectly with the shell-carried internal turbine blades, the said coacting external and stationary blades compressing air which is delivered to increase the propulsion jet constituted by the turbine exhaust.

In the construction of Figures 1, 2 and 3 there is a stationary casing 11 surrounding the unit. The latter comprises a main rotor shaft 12 carrying a set of turbine blades 13, and also sets of blades 14 of the third part of the compressor. Coacting with these latter blades are sets of external blades 15 of the third part of the compressor, such blades being mounted internally of a rotating shell 16. The latter also carries in-

2

ternally sets of turbine blades 17, 18, and at the other end it carries internally sets of blades 19 of the second part of the compressor, such blades coacting with sets of blades 21 mounted externally of a rotor 22 journalled at 23 upon the rotor shaft 12. The rotor 22 is fast with a casing which forms the external shell 24 of the first part of the compressor carrying sets of blades 25 which coact with sets of blades 26 mounted to rotate with the rotor shaft 12.

With regard to the compressor (which, it will be understood, is illustrated as taking one particular form, though it may obviously take many other forms), the three parts into which it is divided, each part comprising several rows of blades, operate at different speeds such that the relative blade speed increases progressively from the inlet end to the outlet end. Thus, the sets of blades 25, 26 of the first part rotate in the same direction, those 26 on the rotor rotating at a high speed and those 25 on the casing 24 at a slow speed. In the intermediate section the blades 21 rotate in the opposite direction to the blades 19 on the shell 16, which latter rotates at medium pace. In the third section the blades 14, 15 rotate in the opposite direction, the blades 14 at a very much greater speed than the blades 15 on the shell 16. Thus, the relative speed in the first section at the inlet end is that of a fast-moving portion minus a slow-moving portion. In the second section it is that of a medium-moving portion plus a slow-moving portion. In the third section it is that of a medium-moving portion plus a fast-moving portion.

In the present instance, for augmenting the thrust, we provide sets of external blades 28 on the rotating shell 16 to coact with sets of blades 29 on the stationary casing 11, and we arrange for the torque reaction imposed upon the casing 11 by the jet augmenter (28, 29) to be counteracted by the discharge from the turbine. For this purpose we mount upon the stationary casing 11 a diffuser 31 having outlets 32 for the turbine exhaust which are inclined as shown.

For starting it is desirable to hold the rotating shell 16 stationary, and one way of achieving this is to provide the shell with a ratchet tooth 34, which can be engaged by a pawl 35. The latter is connected with a diaphragm 36 to which the pressure generated by the jet augmenter (28, 29) is applied, being pressed in the one direction by a spring 37. Thus, in starting, the pawl engages the ratchet tooth and holds the shell 16 against rotation. As soon as combustion occurs and the turbine begins to drive, the shell 16 will revolve in the other direction, whereupon the pressure

generated by the compressor (28, 29) acting upon the diaphragm 36 will move the pawl 35 to an inoperative position. The chamber 38 above the diaphragm is vented by a bleed hole 39 (whereby the return of the diaphragm will be effected slowly) and by check valves 41 whereby the outward movement of the diaphragm can take place quickly.

We prefer, for ignition purposes, to provide a jump spark to carry the high tension current through the space between the stationary casing 11 and the portion 42 of the shell 16 surrounding the combustion chamber 43 in order to avoid the use of slip rings. Such jump spark is indicated at 44 and the parts are circumferentially positioned relatively to the ratchet tooth 34 to ensure alignment when the shell 16 is stationary.

At 46 there is shown a centrifugally-acting valve which is biased by a spring to the open position shown to vent the first part of the compressor, the valve closing automatically as the rotational speed of the unit increases.

Thus, in the construction of Figures 1 to 3 the shell 16 rotates in the opposite direction to that in which the compressor blades 14 (within the interior of the shell) rotate.

Primary air for combustion purposes is led in at a number of angularly-spaced passages of which only one, 84, is shown in the drawing. This primary air is reversed in direction, and in the annular chamber 85 it is mixed with the injected fuel, and combustion takes place in the annular combustion chamber 86 from which there are a number of angularly-spaced outlet passages 87 which reverse the direction of the burning mixture, and in which the rest of the air is mixed for diluent purposes, the mixture then passing to the turbine.

In the construction of Figure 4 there is a stationary casing 50 carrying internally stationary augmenter blades 51 with which coat compressor blades 52 carried externally of a rotatable shell 53, the coating blades 51, 52 compressing air and delivering it along the passage 54 to mingle with the jet delivered along the passage 55 from the turbine. The shell 53 carries internally sets of turbine blades 56, 56, which coat with turbine blades 57 fast on a rotor 58 rotating in the opposite direction to that in which the shell 53 rotates. The rotor 58 also carries externally compressor blades 59 coating with compressor blades 60 carried internally by the shell. In this case the reaction of the stationary casing 50 is taken by stationary blades 61 coating with the last row of turbine blades 56 carried by the shell 53. We show bands 62 uniting the tips of the augmenter blades 52 in each row.

In the embodiments of Figs. 1 and 4, fuel is supplied to the combustion chambers 43 and 63 respectively by means of nozzles *a* and fuel supply pipes *b*.

What we claim as our invention and desire to secure by Letters Patent of the United States is:

1. In an internal-combustion turbine, jet-propulsion unit, fluid admission means, jet creating means, a shell carrying internally some of the turbine blades, a rotor carrying blades within the shell, said shell and rotor rotating in opposite directions, blades carried externally by the shell, stationary blades coating with said external blades, a stationary casing carrying said stationary blades, said casing shaped to direct the air compressed by said coating external and stationary blades to augment the jet constituted by the turbine exhaust and issuing from said means,

and means for substantially balancing the torque reaction on said stationary casing, said means including stationary blades coating with said turbine blades first mentioned.

2. In an internal-combustion turbine, jet-propulsion unit, fluid admission means, jet creating means, a shell carrying internally some of the turbine blades, a rotor carrying turbine blades within the shell, said shell and rotor rotating in opposite directions, blades carried externally by the shell, stationary blades coating with said external blades, a stationary casing carrying said stationary blades, said casing shaped to direct the air compressed by said coating external and stationary blades to mingle with the turbine exhaust issuing as a jet from said means, whereby to augment the jet, and means for substantially balancing the torque reaction on said stationary casing, said means including stationary blades directly coating with said turbine blades first mentioned.

3. In an internal-combustion turbine, jet-propulsion unit, fluid admission means, jet creating means, a shell carrying internally some of the turbine blades, a rotor carrying compressor blades within the shell, said shell and rotor rotating in opposite directions, blades carried externally by the shell, stationary blades coating with said external blades, a stationary casing carrying said stationary blades, said casing shaped to direct the air compressed by said coating external and stationary blades to mingle with the turbine exhaust issuing as a propulsion jet from said means, whereby to augment the jet, and means for substantially balancing the torque reaction on said stationary casing, said means including stationary blades coating with said turbine blades first mentioned.

4. In an internal-combustion turbine, jet-propulsion unit, fluid admission means, jet creating means, a shell carrying internally some of the turbine blades and some of the compressor blades, a rotor carrying turbine and compressor blades within the shell, said shell and rotor rotating in opposite directions, blades carried externally by the shell, stationary blades coating with said external blades, a stationary casing carrying said stationary blades, said casing shaped to direct the air compressed by said coating external and stationary blades to augment the jet constituted by the turbine exhaust and issuing from said means, and means for substantially balancing the torque reaction on said stationary casing, said means including stationary blades coating with said turbine blades first mentioned.

5. In an internal-combustion turbine, jet-propulsion unit, fluid admission means, jet creating means, a shell carrying internally some of the turbine blades, a rotor carrying blades within the shell, said shell and rotor rotating in opposite directions, blades carried externally by the shell, stationary blades coating with said external blades, a stationary casing carrying said stationary blades, said casing shaped to direct the air compressed by said external and stationary blades, to mingle with the turbine exhaust issuing as a jet from said means, whereby to augment the jet, and means for substantially balancing the torque reaction on said stationary casing, said means including stationary blades interposed in the path of the turbine exhaust.
